(57) **CLAIM**

The ornamental design for a wall mounted housing for spill cleanup equipment, as shown and described.

DESCRIPTION

FIG. 1 is a front view of the design of the wall mounted housing for spill cleanup equipment.

FIG. 2 is a right side elevation view of the design of the wall mounted housing for spill cleanup equipment, the left side being a mirror image thereof.

FIG. 3 is a top view of the design of the wall mounted housing for spill cleanup equipment.

FIG. 4 is a rear view of the design of the wall mounted housing for spill cleanup equipment.

FIG. 5 is a perspective view showing the front, right, and top of the design of the wall mounted housing for spill cleanup equipment.

FIG. 6 is a perspective view showing the rear, right and top of the design of the wall mounted housing for spill cleanup equipment.

FIG. 7 is a perspective view showing the front, right and top of the design of the wall mounted housing for spill cleanup equipment; and,

FIG. 8 is a bottom view of the design of the wall mounted housing for spill cleanup equipment.

1 Claim, 4 Drawing Sheets
